E. D. BUMP

CHAIR SEAT MOUNTING

Filed Jan. 3, 1922

UNITED STATES PATENT OFFICE.

EDWARD D. BUMP, OF CLEVELAND, OHIO, ASSIGNOR TO THE BETTCHER STAMPING & MANUFACTURING COMPANY, OF CLEVELAND, OHIO, A CORPORATION OF OHIO.

CHAIR-SEAT MOUNTING.

Application filed January 3, 1922. Serial No. 526,638.

To all whom it may concern:

Be it known that I, EDWARD D. BUMP, a citizen of the United States, residing at Cleveland, in the county of Cuyahoga and 5 State of Ohio, have invented a certain new and useful Improvement in Chair-Seat Mountings, of which the following is a full, clear, and exact description, reference being had to the accompanying drawings.

10 This invention relates to improvements in the mountings for chairs and more particularly to the mechanism for vertically adjusting the seats of chairs of the revolving type. It is the general object of the invention to improve the means for vertically adjusting the seats of such chairs wherein the adjustment is effected by means of a screw additional to the rotary spindle. A further object of the invention is to provide an adjusting means of the character referred to which will distribute efficiently the thrust received by the adjusting screw; also to provide means whereby the said screw will be conveniently and effectively retained against 15 turning in its adjusting sleeve or nut through the ordinary incidents of use to which the chair is subjected. Further and more limited objects of the invention will appear hereinafter and will be realized in 20 and through the construction and arrangement of parts shown in the drawings, wherein Fig. 1 represents a side elevation of the lower part of a chair having my invention applied thereto; Fig. 2 a detail in sectional elevation of the lower portion of the adjusting screw and of the parts cooperating therewith; Fig. 3 a sectional elevation taken at right angles to Fig. 2; and Fig. 4 a sectional view corresponding to the line 4—4 25 of Fig. 2.

Describing by reference characters the various parts illustrated herein, 1 denotes the legs and 2 the hub of a chair of the type referred to, the hub receiving therewithin 35 the lower end of the spindle 3. This spindle supports a head 4, in the form of a casing which is reciprocably mounted upon the spindle. 5 denotes one of a pair of spider arms supporting the seat 6 and having extensions 5^a pivotally connected to the casing head 4 as indicated at 5^b. 7 denotes the usual springs which yieldingly resist the tilting of the chair seat.

The casing 4 carries a nut which, in the 55 embodiment herein disclosed, may be con-

stituted by an internally threaded sleeve 8 connected to the casing 4 by arms 9. The construction thus far described is one which is ordinarily employed in revoluble tilting chairs and, in its details, constitutes no part 60 of my invention.

Threaded into the sleeve nut 8 is the adjusting screw stem 10 by means of which the seat carrier comprising the casing head 4 is raised and lowered on the spindle 3, 65 thereby to raise and lower the chair seat. The means for mounting and operating the said screw stem are shown more particularly in Figs. 2, 3 and 4. Above its lower end, the stem of the screw 10 is provided with 70 two opposed flattened surfaces 11, there being a shoulder 12 formed above each of said surfaces. Below the portion comprising the surfaces 11, the screw stem is further reduced, as indicated at 13, there being a horizontal shoulder 14 provided between the upper end of such reduced portion 13 and the body of the stem thereabove.

The flattened surfaces 11 are for the reception of the hand wheel by which the 80 screw is rotated, said hand wheel having an aperture therethrough corresponding in shape to the cross section of that part of the stem which includes the surfaces 11, whereby a driving connection is established 85 between said wheel and said stem. The hand wheel comprises an upper and outer section, made preferably of sheet metal and comprising a disk 15 having at its periphery a downturned cylindrical flange 16 tightly 90 gripping the periphery of a washer 17 constituting part of a lower and inner section and having a downwardly extending hub 18 provided on opposite sides thereof with downwardly extending rounded lugs or projections 19. The aperture through the disk 15 and the hub 18 is so shaped as to conform to the cross section of that part of the screw stem which includes the surfaces 11. By the construction described, a driving connection is formed between the outer 95 operating portion 15, 16 of the hand wheel and the said stem.

It will be noted that the bottom of the hub 18, between the lugs or projections 19, 105 is in the same plane as the shoulder 14. The screw stem 10 is supported jointly by said hub and shoulder on the top of an extension 21 of a collar 20, the said collar being mounted upon the spindle 3 and shown as connect- 110

ed thereto by a pin 22 and the said extension having a bore 21^b receiving and approximately sizing the reduced portion 13 of said stem. The collar in turn is support-
5 ed upon the upper cap 23 of the hub 2.

It will be noted, by reference to Figs. 2 and 3, that the extension 21 of the collar is provided with concave notches 21^a complementary to the convex lower ends of the 10 projections 19, but that, when the projections are in register with said notches, a clearance is provided between the notches and projections. This not only relieves the projections and notches of wear, but also prevents the 15 projections from riding too easily out of the notches during the ordinary use of the chair and thus prevents the screw 10 from turning in its nut 8 during such ordinary operation.

While I have shown my invention as applied to a non-reciprocable spindle having a reciprocable head casing thereon, it is obvious that it may be used with a reciprocable spindle having the head casing rigid therewith, in which case the connecting pin 22 will be omitted, allowing the spindle to move up and down through the collar which will be supported solely and directly by the plate 23.

Having thus described my invention, what 30 I claim is:

1. In a device of the character described, the combination of a spindle, a seat carrier thereon, a nut connected with said carrier, a collar mounted on said spindle and having 35 a projection provided with a bore, a screw stem threaded in said nut and having its lower end mounted in said bore, the portion of the screw stem above such collar extension having a shoulder thereon, and a hand 40 wheel on said stem below said shoulder and engaging the latter and having a driving connection with said stem, said wheel having a hub bearing against the upper surface of the collar projection.

45 2. In a device of the character described, the combination of a spindle, a seat carrier thereon, a nut connected with said carrier, a collar mounted on said spindle and having a projection provided with a bore, a screw 50 stem threaded in said nut and having its lower end mounted in said bore, the portion of the screw stem above such collar extension being non-circular in section and having a shoulder above such section, and a hand

wheel mounted upon the non-circular portion of said stem and adapted to engage said shoulder with its upper surface and provided with a central portion or hub adapted to engage the collar extension. 55

3. In a device of the character described, the combination of a spindle, a seat carrier thereon, a nut connected with said carrier, a collar mounted on said spindle and having a projection provided with a bore, a screw stem threaded in said nut and having its lower end mounted in said bore, a hand wheel comprising a washer mounted on said stem and having a depending hub, a disk also mounted on said stem whereby the latter is adapted to be rotated by said 60 wheel, and having a peripheral flange closely embracing said washer, the said hand wheel having a driving connection with said stem and the stem having a shoulder overhanging and engaged by the central 65 portion of said disk and having its lower end portion reduced and extending below said hub, said stem having a shoulder in the plane of the bottom of said hub whereby the said shoulder and hub jointly support 70 the said stem from the collar extension, and interengaging projections and notches carried by said hub and extension to resist the rotation of said screw. 75

4. In a device of the character described, the combination of a spindle, a seat carrier thereon, a nut connected with said carrier, a collar mounted on said spindle and having a projection provided with a bore, a screw stem threaded in said nut and having its lower end mounted in said bore, a hand wheel comprising a washer mounted on said stem and having a depending hub, a metal disk also mounted on said stem and having a peripheral flange closely embracing said washer, the said hand wheel having a driving connection with said stem and the stem having a shoulder overhanging and engaged by the central portion of said disk and having its lower end portion reduced and extending below said hub, said stem having a shoulder cooperating with the bottom of said hub jointly to support the said stem from the collar extension. 90 95 100

In testimony whereof, I hereunto affix 105 my signature.

EDWARD D. BUMP.
